UNITED STATES PATENT OFFICE.

MYRON M. METZINGER, OF BLAIR, NEBRASKA.

CONCRETE-BLOCK WALL STRUCTURE.

1,294,509.

Specification of Letters Patent. Patented Feb. 18, 1919.

Application filed August 16, 1917. Serial No. 186,617.

To all whom it may concern:

Be it known that I, MYRON M. METZINGER, a citizen of the United States of America, residing at Blair, in the county of Washington and State of Nebraska, have invented certain new and useful Improvements in Concrete-Block Wall Structures, of which the following is a specification.

My invention relates to improvements in concrete block walls having complete outer and inner face blocks with connected hollow spaces therebetween and cross-bonding interlapping-legs through the space between outer and inner blocks; and the objects of my improvements are as follows:

First, to provide the minimum number of differently and simply-shaped blocks for laying up the walls of any rectangular inclosure, or standardized sizes of curved or circular walls for round inclosures.

Second, to supply a simple and effectual mortar bond for the bed and heading joints of all general work with means adaptable and easily added for special requirements.

Third, to provide metal reinforcement of each unit or block and means for continuously connecting all the units of reinforcement and blocks in a course of wall work, as well as to connect the different superimposed courses of blocks and reinforcements in a wall, and,

Fourth, to facilitate the exclusion of inwardly penetrating moisture through the completed wall structure, as well as the thorough drying out of newly erected structures, and thereby avoid special exterior coatings on the completed structures.

I attain these objects by the structural elements illustrated in the accompanying drawings in which—

Figure 1 is a fragmental perspective view of a building corner made of such a wall structure, showing the top and outside face of a portion of wall three courses high; Fig. 2, a vertical cross-section of such a wall, taken on the broken line 2—2 of Fig. 1; Fig. 3, a like section, taken on the broken line 3—3 of Fig. 1; Fig. 4, a top or plan view of a course of blocks arranged to properly bond as the next course in height on the wall as shown in Fig. 1; Fig. 5, a perspective view of the regular outside stretcher blocks for straight walls; Fig. 6, a perspective view of the outside angle or corner block for each course; Fig. 7, a perspective view of the

closer block for one side of an inside corner of every course; Fig. 8, is a fragment of a plan of curved wall, such as is used for silos and grain bins; Fig. 9, an enlarged plan of a curved wall stretcher block, disclosing the manner of metal reinforcement; Fig. 10, a plan of a regular corner block, with its embedded reinforcing strip of sheet-metal correctly placed; Fig. 11, a perspective view of a bent end portion of the flat bar or sheet-metal block-reinforcing strip and the vertical connecting or locking rod; Fig. 12, an enlarged perspective view of the smaller end of an outside corner block; and Fig. 13, is an enlarged vertical section of a small block fragment, taken through one of the hemispherical mortar dowel pits. In all of these views similar reference numerals indicate similar parts of the structure.

Aside from such cut blocks and closers as may be required to fit around wall openings and for adjusting lengths of walls, there are only three shapes of blocks in this general structure; these are shown in Figs. 5, 6 and 7, and are of shape described as follows:

The stretchers for regular straight walls, both inside and outside faces, are of the same U-shape, consisting of the straight body part 4, having at its ends the right-angularly-disposed cross-bonding legs 5 and 6. For curved walls, silo or grain-bin structures, these stretchers are modified only by curving the body portions 4 to correctly line the outer and inner wall faces as required, and adjusting the lengths of the bodies to bring the inner and outer bonding legs 5 to coincide longitudinally for correct radial or cross bond, as shown in Fig. 8.

The outside corner blocks of a course each consist of an L-shaped body comprising a base limb 7 of length equal to the regular wall stretchers and a branch limb 8 of one-half that length. The projecting end of each limb is provided with an inwardly-standing bonding-leg 9 to coincide with and be disposed between the bonding legs 10 and plain ends 11 of the adjoining closers in adjacent, subjacent and superimposed courses,—see Figs. 1 and 4. These corner blocks are inverted, and reversed in position, for each successively imposed course of blocks in the wall.

The inside corner closers or blocks are each composed of a straight stretcher body 9, having on one end only the angular out-

wardly standing cross-bonding leg 10; the opposite plain end 11 being of sufficient length to lap and bond with the bonding legs 8 on the short limbs 6 of the outside corner blocks of the adjacent courses above and below.

The hemispherical dowel pits 12 are made in both bedding faces of all the blocks, disposed directly opposite on opposite faces of 10 the block, so as to register and stand opposed in all opposed block faces on the same mortar bed or joint. To attain this agreement of position of pits in the opposed bedding faces for all the required positions of 15 the blocks in the wall, the longitudinal rows of pits are disposed centrally of the bed faces of the bodies of the blocks and the cross rows centrally of the bed faces of the cross-bonding legs; widths of legs and 20 bodies being made equal and the pits composing each pair of pits spaced equally lengthwise of each leg and at the center of the length of each body part; and the pair of pits at the longitudinal center of each 25 body bed register with the end or angle pits of the interbonding subjacent and imposed stretcher blocks. It will be observed, by noting Figs. 1 and 4, that this arrangement disposes the pits in pairs of cross-rows in the 30 wall, a pair of cross rows at each place of cross-bonding; also giving three longitudinal rows of pits in the wall; the central one of which being kept in longitudinal alignment controls the thickness of wall as well as 35 the width of the hollow between inner and outer face blocks. These pits being carefully filled with a strong mortar form an anchoring ball, as illustrated at 12 in Figs. 3 and 13, that for any ordinary requirement 40 prevents any possible lateral or horizontal shift of super-imposed blocks or courses of blocks in a wall.

A further advantage of the above disposition of these bonding pits will be apparent 45 in the reinforced blocks and increased bonding means combined therewith for walls where greater resistance to very heavy strains are required,—which is set forth as follows: The perforate reinforcing strips 16 50 are made of flat bar iron or heavy sheet metal. The angles 18 to shape around the corners and to form the bonding-leg reinforcing tongues or legs 21, are made by bending the metal strip obliquely flatwise 55 upon itself as shown in Fig. 11. When this metal reinforcement is bedded in the center or core of the blocks, as disclosed in Figs. 2, 3, 9 and 10, and the block has become indurated, these angles are quite as rigid and 60 strong as if stamped integrally angular from the sheet metal. As shown in Fig. 9 the intermediate body portion 16 is stamped out with the required edgewise curvature and the leg angles made as in other cases. 65 All of these reinforcing strips have the lon-

gitudinal rows of perforations 17, as shown, to give the strip a more secure bed in the block and to reduce to the minimum separation or division of the block by the strip. The terminal or outer end perforations 19 at the outer ends of the reinforcement legs 21, are of size and are set coincident with and form part of the walls of the dowel pits 19 in the bonding legs. These dowel pits extend vertically clear through the legs and 70 those in superimposed courses register with each other, as shown in Fig. 3. Vertical bonding or dowel rods 22, as shown in Fig. 11, of smaller diameter to be flushed in around by mortar, may be seated in these 75 continuous vertical pits; or where the maximum of strength and bond are required, close-fitting vertical dowel rods are seated therein. Making this vertical dowel-rod continuous, I have a structure reinforced 80 and bonded against all the strains to which structural walls are subjected.

The V-shaped vertical grooves 20, are disposed in the ends of the blocks and set nearest to the face thereof. In the walls they 85 form square vertical wells down through the heading joint, see Figs. 1 and 4, of sufficient size to readily take a filling of mortar. This facilitates full flushing of the heading joints with mortar and forms a heading joint lock, 90 preventing any possible lateral movement of either adjoining block. It serves as an anchorage for any rake-out pointing of the heading joints and facilitates attaining a heading joint that is air and water tight.

In walls laid of blocks proportioned in sizes as shown, there are the large flue hollows 14, vertically continuous, and the spaces between the recurring cross-bonding legs. The inwardly extended ends of the 95 legs are all spaced away from the backs of the opposite block bodies, to form the narrow communicating slits 13 between the flues. By this means the new wall is easily dried, by leaving external openings at top 100 and bottom of the wall hollow. To further render the wall impervious or weather proof, the entire inside surface of the body and bonding legs of the outside wall blocks, have a water proof coating or layer 15. 105 This coupled with the use of a water-proof mortar in which the blocks are laid excludes all weather moisture or dampness from the inner face of the wall, and avoids the necessity of any exterior wall treatment that 110 would mar the color or natural texture of the outer wall surface.

I claim:

1. A concrete-block wall-structure, comprising opposite face walls of like blocks 115 laterally spaced to form a hollow wall, inwardly projecting legs on the backs of the blocks to interlap with the legs of blocks in courses below and above of the opposite face wall to bond the face walls across the hol- 120

low, reinforcing bars disposed lengthwise of the wall in the bodies of the blocks, integral legs on the reinforcing bars standing angularly therefrom and disposed into the legs of the blocks and having terminal eyes therein, and a central longitudinal row of vertical locking rods disposed through said interlapping block legs and terminal eyes.

2. A concrete-block wall-structure, comprising opposite face walls of like oblong-bodied blocks laid up in stretcher bond, inwardly disposed legs at the ends of the blocks to interlap with the legs of blocks in courses below and above in the opposite face wall to cross-bond the face walls together, a row of four mortar dowel pits disposed in each bed-face of each block body parallel with the wall face of the block, the end pits of the rows spaced equally from the adjacent ends of the block and from the wall face thereof, the intermediate pair of pits in each row disposed one on each side of the center of length of the block and each pit spaced from said center a distance the same as the end pits are spaced from the ends of the block, and a dowel pit disposed in each bed-face of the legs in transverse alinement with said end pits and spaced from the wall

faces of the blocks one-half the thickness of the wall structure.

3. A concrete-block wall-structure, comprising opposite face walls of blocks, reinforcing bars disposed in the blocks longitudinally of the wall-structure, inwardly-projecting legs on the reinforcing bars, a terminal eye on each leg and disposed in vertical alinement with like eyes below and above on the legs of reinforcing bars in the blocks of the opposite face wall, and rods disposed at the center of the wall-structure and vertically endwise through said aligned eyes to lock the opposite face walls together.

4. A concrete-block wall-structure, comprising opposite face walls of like blocks, inwardly-projecting legs on the backs of the blocks to interlap for cross-bonding with the legs of blocks in courses below and above in opposite face walls, and mortar dowel pits disposed in the bed faces of the bonding legs and spaced from the wall faces of the blocks distances equal to one-half of the thickness of the wall-structure.

In testimony whereof I have affixed here-to my signature.

MYRON M. METZINGER.
